UNITED STATES PATENT OFFICE.

ARTHUR SMITH, OF SCHENECTADY, NEW YORK, ASSIGNOR TO GENERAL ELECTRIC COMPANY,
A CORPORATION OF NEW YORK.

MOTOR-STARTING PANEL.

No. 890,719.

Specification of Letters Patent. Patented June 16, 1908.

Application filed January 17, 1907. Serial No. 352,737.

To all whom it may concern:

Be it known that I, ARTHUR SMITH, a citizen of the United States, residing at Schenectady, county of Schenectady, State of New York, have invented certain new and useful 5 Improvements in Motor-Starting Panels, of which the following is a specification.

This invention relates to means for controlling electric motor circuits, and has for its 10 object the provision of a device of this character whereby the main armature circuit is automatically opened by means external to the controlling device itself.

My invention relates more specifically to 15 controlling devices of the type used in starting electric motors. In this type of apparatus, commonly known as starting rheostats, the controlling arm is ordinarily spring-pressed to the "off" or starting position and 20 is held in the "on" or running position by a no-voltage release magnet. Upon failure of voltage, the arm returns to the off position and the main circuit is broken on the rheostatic contacts. This arrangement is objectionable in many instances, as for instance in 25 the larger starters where the current is heavy, in which case the contacts are burned and must be replaced.

In carrying out my invention, I provide in 30 connection with an ordinary starting rheostat having a spring-pressed controlling arm and a no-voltage release magnet, a circuit-breaker arranged to open the main circuit before the arm reaches the "off" position. 35 The circuit-breaker is preferably of the automatic type and may be provided with overload magnetic features so as to open the circuit upon the occurrence of an overload.

In the accompanying drawing I have 40 shown a starting panel equipped with my invention.

In the drawings, Figure 1 is a plan view of the device; Fig. 2 is a side elevation of the same; and Fig. 3 is a diagram of the circuits.

45 Referring to the drawing, 10 is an insulating base of some material, such as slate or soapstone, provided with a series of contact segments 11 forming the terminals of starting resistance 12. The controlling arm 13 pivoted at 14 is adapted to engage these contacts so as to cut out starting resistance in starting up the motor. The arm is normally in starting position against the stop 15 and as it is moved to the right, starting resistance is cut 50 out until it reaches the no-voltage magnet 16.

at which point it is held, the resistance being short-circuited.

Mounted upon the base 10 in proximity to the rheostat is a circuit-breaker or switch. This circuit-breaker may be of any well known construction, and is preferably of the automatic magnetic type. In the drawing I have illustrated a specific form of circuit-breaker in which there are two independently operated arms 17 and 18 having operating 60 handles 19 and 20, respectively. Each arm is spring-pressed to the open position by a spring 21, and closes the main circuit through a laminated brush 22 and carbon contacts 22^a. The breaker arms are held closed by means of latches 23 engaging the toggle 24, one of said latches being mounted on each of the handles 19 and 20. An overload coil 25 is provided preferably between the two arms, and a T-shaped element 26 65 pivoted at 27 is adapted to be attracted by the magnet 24 so that the lugs 27^a strike the latches 23 a hammer blow to release the arms, which are thereupon opened in response to the tension of the spring 21. The hammer element is further provided with a 70 guide 28 and the adjusting screw 29. As before stated, this general type of circuit breaker is well known in the art and is simply shown and described here for purposes of 75 illustration. Pivoted to a bracket 30, between the circuit breaker and the rheostatic contacts is a forked or Y-shaped element, the arms 31 of which are arranged to engage the latches 23 so as to trip the same in a manner similar to that of the hammer arm 26. 80 This forked element is provided with a projection 32 which extends into the path of the rheostatic controller arm. This arm is provided with a finger 33 which is extended outward so as to engage the projection 32 as it 85 moves towards starting position. The finger is yieldingly held against a stop 33^a by means of a spring 34, and the end of the finger is beveled so that as it moves to the off position in response to its spring on the arm, it will engage the projection 32, and as the latter rides over the finger it will be raised thereby engaging the latches 23 to trip the breaker. 90 As the arm is moved in the opposite direction, that is towards the magnet 16, the finger will engage the projection but the spring 34 will allow the finger to pass without tripping the breaker.

100 The operation of my device will be clear 110

from the above description taken in connection with the diagram of the connections shown in Fig. 3. The magnet 16 is shown connected across the line, although of course it may be connected in the shunt field circuit or in any other desired manner. The overload coil 25 is in series with the armature A and the controlling arm 13. To start the motor, the circuit-breaker is closed by means of the arms 19 and 20, and the controlling arm 13 is moved to running position, in which it is held by means of the magnet 16. Upon failure of voltage, the arm will fly to the off position and as it does so, the finger 33 will engage the projection 32 and trip the circuit-breaker thereby opening the armature circuit at the carbon contacts 22 instead of on the contact segments.

I have shown the circuit-breaker as arranged midway between the starting and running positions of the controlling arm but this position may be varied as may also the construction of the switch or circuit-breaker. The construction of the rheostat and other features of my device may also be modified without departing from the spirit of my invention, the scope of which is set forth in the claims annexed hereto.

What I claim as new and desire to secure by Letters Patent of the United States, is,—

1. The combination with a starting rheostat having a spring-returned arm and a no-voltage magnet for retaining the same in running position, of an automatic switch in circuit with and operated independently of said arm, and means whereby said switch is automatically opened during the movement of the arm to starting position.

2. The combination with a starting rheostat having a spring-returned arm and a no-voltage magnet for retaining the same in running position, of an automatic switch in series with and operated independently of said arm, and means whereby said switch is opened by the arm during the return of the latter to starting position.

3. The combination with a starting rheo-

stat having a controlling arm biased to an off position and a no-voltage magnet for retaining the same in running position, of an automatic circuit-breaker in series with said arm, and means whereby it is tripped by said arm as the latter returns to starting position.

4. The combination with a starting rheostat having a spring-returned arm and a no-voltage magnet for retaining the same in running position, of an automatic magnetic circuit-breaker in series with the arm, and means whereby it is tripped by the arm during the return of the latter to starting position.

5. The combination with a rheostat provided with automatic no-voltage release features, of an automatic overload circuit breaker arranged to be tripped as the controlling element of the rheostat moves towards starting position.

6. The combination with a rheostat provided with automatic no-voltage release features, of an automatic overload circuit-breaker having a releasing element arranged in the path of the rheostatic controlling element so as to trip the circuit-breaker as the element moves to starting position, and means whereby the element passes the breaker without tripping the same as it moves toward running position.

7. The combination with a starting rheostat having a spring-returned arm and a no-voltage magnet for retaining the same in running position, of an automatic magnetic circuit-breaker in series with the arm, and a device carried by said arm for engaging the circuit-breaker and tripping the same as it moves to starting position said device not affecting the circuit-breaker as it moves towards running position.

In witness whereof, I have hereunto set my hand this 15th day of January, 1907.

ARTHUR SMITH.
